[57] CLAIM

The ornamental design for a cosmetic hair extractor, shown and described.

DESCRIPTION

FIG. 1 is a perspective view of the cosmetic hair extractor embodying the design;

FIG. 2 is a front elevational view thereof;

FIG. 3 is a rear elevational view thereof;

FIG. 4 is a side elevational view thereof;

FIG. 5 is a top plan view thereof; and,

FIG. 6 is a bottom plan view thereof.

The cord is shown partially broken away in the several views to indicate indeterminate length.

FIG. 2.

FIG. 3.

FIG. 5.

FIG. 4.
